UNITED STATES PATENT OFFICE.

BÉLA GERESEN, OF BUDAPEST, AUSTRIA-HUNGARY, ASSIGNOR TO UNDERWOOD TYPEWRITER COMPANY, OF NEW YORK, N. Y., A CORPORATION OF NEW JERSEY.

TABULATOR FOR TYPE-WRITERS.

No. 852,324.

Specification of Letters Patent.

Patented April 30, 1907.

Application filed January 12, 1905. Serial No. 240,779.

To all whom it may concern:

Be it known that I, BÉLA GERESEN, a subject of the King of Austria-Hungary, residing at Budapest, in the Kingdom of Austria-Hungary, have invented certain new and useful Improvements in Tabulators for Type-Writers; and I do hereby declare the following to be a full, clear, and exact description of the invention, such as will enable others skilled in the art to which it appertains to make and use the same.

My invention relates to a tabulator device for typewriters.

The essential feature of my invention consists in providing a rotating graduated stop coöoperating with the tabular stops, means being provided for turning and fixing the said rotating stop in its different positions and means being provided to actuate the carriage release.

Further means may be provided to allow the tabular stops to yield in the direction permitting to turn the rotating stop when adjacent to one of said tabular stops.

My invention aims also to improve the brake acting on the carriage, when this latter is released on the working of the tabulator.

The scope of my invention will be more fully described and claimed hereinafter.

In the accompanying drawing, which illustrates an embodiment of my invention applied on the machine-type known under the name "Underwood," Figure 1 is a rear elevation of the upper part of the machine provided with the tabulator. For the sake of clearness several details of the typewriter are omitted. Fig. 2 is a side elevation of the tabulator device with the adjacent parts of the typewriter. Fig. 3 shows the cross section of the oscillating stop rod with the tabular stop when yielding on the action of the rotating graduated stop. Fig. 4 is the front view of the tabular knob with the dial or tabular scale. Fig. 5 shows diagrammatically the improved wedge shaped brake bar in plan view. Fig. 6 shows a modified form of the rotating graduated stop. Fig. 7 shows the preferred form of finger piece for setting the denomination stops.

A is the main frame of the machine and B is the carriage. Both are of the well known construction.

1 is a spindle pivoted in the brackets 2, 2 of the main frame and 3 is a coiled spring the ends of which are secured respectively to the spindle 1 and the adjacent bracket 2. On the spindle 1 is secured a single-piece graduated stop 4 provided with a plurality of radial steps 5. The distance from each step to the next corresponds with the space of the letters of the typewriter, and with the carriage-feeding movements. On the spindle 1 a sleeve 6 is loosely mounted to turn freely relatively to said spindle. From the said sleeve a lever 7 extends downwardly the end of which is bent outwardly at a right angle. A substantially horizontal thumb 8 projects backward from sleeve 6 and rests on the well known carriage releasing lever 9. An upward projecting arm 10 of the sleeve 6 bears 70 the brake plate 11 covered with leather or the like and acting against the flat brake bar 12 mounted on the carriage.

As shown in Fig. 5, the bar 12 is slightly wedge shaped so that the acting face of said bar is slightly divergent to the path of the carriage, the braking effect increasing thus toward the end of the travel of the carriage.

13, 13 are brackets secured to the carriage B and supporting the toothed tabular stop rod 14, the ends of which are pivoted in said brackets 13. A spring 15 fastened with its ends respectively to the tabular stop rod 14 and to the left bracket 13 acts to return the rod 14 in its normal position shown in Fig. 2 85 when it was turned in the position Fig. 3. On the brackets 13 abutments 16 may be formed (see also Fig. 3) fixing the normal position (Fig. 2) of the stop bar.

The spindle 1 supports near its left end a bevel pinion 17 fixed thereto and meshing with the pinion 18 supported by a vertical shaft 19 journaled in bearings 20, 21 secured to the main frame A. To the lower end of the shaft 19 is fixed the bevel pinion 22 meshing with a pinion 23. The bevel pinion 23 is secured by means of its hub 24 on a horizontal spindle 27 to rotate together with said spindle but to allow a longitudinal shifting of the spindle in the hub of the pinion. The spindle 27 is journaled in the bearings 25 and 28, the former attached by means of the bracket 26 to the bearing 21 and the latter secured to the main frame A. The front end

of the spindle 27 is provided with a knob 29 having a recess 30 with roughened surface adapted to receive the thumb of the operator when turning the knob.

5 On the main frame A is secured a dial 31 and on the part of the spindle 27 between the frame and the knob a pointer 32.

10 A ring 33 forming a shoulder is fixed to the spindle 27 and a spring 34 is located between the bearing 25 and the shoulder 33 secured respectively to said bearing and shoulder. When the knob 29 is turned or pushed the spring 34 is stretched or compressed and will return after the knob is released this latter together with the spindle 27 in the initial position.

15 The spindle 27 is fitted with a disk 35 toothed on its periphery, the teeth corresponding with the scale of the dial 31. On a support secured to the main frame a pin 36 extending toward the toothed disk 35 is arranged to enter the corresponding recess between the teeth of the disk 35 when this latter is approached to the pin 36 by pushing the knob 29.

20 The device operates in the following manner: When a number of four figures for instance should be written, the knob 29 is turned until the pointer reaches number 3000 on the dial. The knob is then pressed in, whereby the position of the knob and the spindle 27 is secured from rotation by the pin 36 entering the recess of the disk 35 being in front of the pin 36. The pin 36 and the recesses of the disk 35 may be wedge shaped or tapered to facilitate the operation. By turning the knob 29, the spindle 27 is rotated and the movement of this spindle is transmitted by means of the bevel pinions 23, 22, 40 the shaft 19 and the pinions 18, 17 to the spindle 1, turning thus the graduated stop 4 with an angle corresponding to five steps on the stop 4, because 1,000 corresponds to the fifth degree of the scale of the dial. By 45 pushing the knob inwardly, the spindle is shifted longitudinally in the hub of the pinion 23 without altering the position of this latter fixed by the pin 36 engaging the disk 35.

50 The end of the spindle 27 is disposed in front of the bent end of the arm 7 so that on shifting the spindle 27, the lever 7 and the sleeve 6 is slightly turned on the spindle 1. Thereby on the one hand the thumb 8 depresses the carriage releasing lever 9 and is pressing on the other hand by means of the arm 10 the brake plate 11 against the brake bar 12. The carriage thus released will jump until the stop 37 mounted adjustably on the 55 tabular stop rod 14 will abut against the fifth step 5 of the graduated stop 4 brought by having turned the knob 29 into the path of the tabular stops 37, 38. The movement of the carriage is governed by the action of the 60 brake 11, 12 which increases toward the end 65

of the travel of the carriage owing to the wedge shape of the bar 12. The knob 29 is then released by the operator, whereupon the parts are brought by means of the springs 3 and 34 in their original position. The pressure exerted on the carriage release lever 9 ceasing, the escapement of the carriage, which is designated by C is put in action and stops the carriage in the position determined by the stop 37 and by the fifth step of the rotary stop 4.

70 If a number of five figures should be written, the rotary stop will be moved so far, that the sixth step is turned into the path of the tabular stop 37 of the carriage and if a number of three figures must be written in the column of numbers, the rotary stop 4 will be turned so that the fourth step may extend into the path of the stop 37, and so on.

75 It will be understood that the operator 80 must maintain pressure upon the finger-piece 30 until the carriage is arrested by the stops, and that the tooth 36 is intended merely to lock the shaft 27 against rotation.

85 When the carriage is stopped by the mutual action of the stops 4 and 38, the operator releases the knob 29, and the stop 4 rotates to normal position. If now the knob 29 is immediately turned again without first writing anything, the rotary stop 4 can easily be 90 turned by said knob, to any desired point, in spite of the fact that stop 38 is in front of the stop 4 (see Fig. 2). The stop 4 abutting against the stop 38 tilts the stop and the pivoted rod 14 (Fig. 3) until 4 can pass by 38. In other words, by the rotation of the stop 4, the column stop 38 can be turned out of the way, effecting a rotation of the bar upon which the stop 38 is mounted. The carriage 95 may then be released and then arrested by the engagement of the next column stop with the selected stepped shoulder on stop 4.

100 It will be seen, that the stops 37, 38 limit the travel of the carriage, but do not hinder the rotation of the graduated stop 4.

105 It will be understood, that the details of my invention may be varied in different ways without departing from the scope of my invention. Thus the helicoidal graduated stop 4 need not always be provided with 110 steps but can be formed as a continuous helical surface, as shown in Fig. 6 and the tabular stops arranged on the rod 14 may be fitted with similarly formed oblique faces. Instead of the knob shown in Fig. 4 the knob 115 shown in Fig. 7 may be used, which is provided with a wing 39 for turning the knob by means of the index, while the thumb resting on the knob 40 serves for pushing in this latter. The device for turning the rotary stop 120 may be of any suitable construction.

125 Having now described my invention, what I claim is:—

1. In a typewriting and tabulating mechanism, the combination with a carriage, of a 130

- tabulator comprising a carriage-releasing lever, a substantially helicoidal rotary stop mounted on a spindle parallel to the path of the carriage, a sleeve mounted on said spindle and supporting a brake plate which is adapted to co-act with a brake bar, an arm coacting with said releasing lever, and means to rotate said spindle independently of the sleeve and also to turn said sleeve independently of the spindle.
2. A tabulator for typewriters, comprising a carriage-releasing lever, a substantially helicoidal rotary stop mounted on a spindle parallel to the path of the carriage, a sleeve mounted on said spindle and supporting a brake plate which is adapted to co-act with a brake bar, an arm co-acting with said release lever, a sleeve-operating lever extending into the path of a spindle which is rotated and shifted axially by means of an operating knob and which rotates by means of a suitable gearing said helicoidal stop, means to secure the operating spindle against rotation during the axial shifting, stops arranged adjustably on a rod which is pivoted on the carriage, and springs to return the parts to their initial positions.
3. In a tabulating mechanism, the combination with stops to arrest the carriage, of a carriage-releasing device, a key connected to said carriage-releasing device, and means also operable by said key, to control the speed of the released carriage, including a brake-plate operated by the key, and a brake bar extending along the carriage to co-operate with said brake-plate throughout substantially the entire range of travel of the carriage, the active face of said brake bar being slightly divergent to the path of the carriage and co-operating with said brake-plate to force said key to recede during the entire run of the carriage and in opposition to the pressure of the operator's finger on the key, thereby tending to gradually increase the pressure between the finger and the key, and hence between the brake-plate and the brake-bar.
4. In a tabulating mechanism, the combination with stops to arrest the carriage, of a carriage-releasing device, a key connected to said carriage-releasing device, and means also operable by said key to control the speed of the released carriage, said controlling means including one member set at an angle to the direction of the carriage movement and extending substantially the entire length of the travel of the carriage, and a second member caused by means of pressure on said key to rub against the angle member during substantially the entire travel of the carriage; said angle being such as to enable the carriage to cause said rubbing members to co-operate to force said key to recede during the entire run of the carriage and in opposition to the pressure of the operator's finger on the key, thereby to increase the pressure between the finger and the key, and hence between the rubbing members, to an extent dependent upon the length of travel of the carriage.
5. In a typewriting and tabulating mechanism, the combination with a carriage, of a rotary helicoidal stop, an axially shiftable rotary key connected by gearing to said helicoidal stop, an index for said key, and a carriage-releasing mechanism operable by shifting said key.
6. In a typewriting and tabulating mechanism the combination with a carriage and a rotary helicoidal stop, of a pinion connected to said stop, a vertical shaft having a pinion and engaging said stop pinion, a horizontal shaft geared to said vertical shaft and extending forwardly therefrom, a key mounted on the front end of said horizontal shaft, and an index for said key.
7. In a typewriting and tabulating mechanism, the combination with a carriage and a rotary helicoidal stop, of a pinion connected to said stop, a vertical shaft having a pinion and engaging said stop pinion, a horizontal shaft geared to said vertical shaft and extending forwardly therefrom, a key mounted on the front end of said horizontal shaft, an index for said key, and carriage-releasing means including a member operable by a longitudinal movement of said horizontal shaft.
8. In a typewriting and tabulating mechanism, the combination with a carriage, of a rotary helicoidal stop, a rotary key axially shiftable and connected by gearing to said helicoidal stop, a curved rack 35 connected to said key and movable by a depression of the key, and a registering tooth 36 to engage said rack when the key is shifted.
9. In a typewriting and tabulating mechanism, the combination with a carriage, of a rotary helicoidal stop, a rotary key axially shiftable and connected by gearing to said helicoidal stop, a circular rack 35 connected to said key and movable by the shifting of the key, a registering tooth 36 to engage said rack when the key is shifted; and a carriage-releasing mechanism operable by the shifting of said key.
10. In a typewriting and tabulating mechanism, the combination with a carriage, of a carriage-releasing mechanism, a rotary helicoidal stop, means for rotating said stop, and means distinct from said rotating means for locking said stop against accidental rotation from its adjusted position during the movement of the carriage after the latter is released.
11. In a typewriting and tabulating mechanism, the combination with a carriage, of a helicoidal stop, a shaft with which said stop rotates, a spring upon said shaft for returning said stop, a rotary axially shiftable key, gearing between said key and said shaft and

means rendered effective by the shifting of said key for locking said stop against accidental rotation.

12. In a typewriting and tabulating mechanism, the combination with a carriage, of a rotary helicoidal stop, a column stop bar, and column stops adjustable along said bar, the latter being pivoted so that when any column stop stands opposite said helicoidal stop, a rotation of the latter will force the column stop and bar to swing out of the way.

13. In a typewriting and tabulating mechanism comprising a carriage, the combination with a plurality of column stops adjustable to arrest the carriage at different points in its travel, and a stop to co-operate with any of said column stops, of a carriage-releasing device, a key connected to said carriage-releasing device, and means brought into action by the carriage-releasing movement of said key to control the speed of the released carriage; said controlling means including two relatively movable members caused by the carriage-releasing action of said key to rub together during substantially

the entire range of travel of the carriage, one of said rubbing members being set at an angle to enable the carriage to effect throughout its run a gradual recession of one of said rubbing members, and means being provided to cause such recession to effect increased pressure between the rubbing members, to cause the final frictional opposition of said rubbing members to the movement of the carriage to be proportioned to the length of run of the carriage to the nearest column stop.

14. In a typewriting and tabulating mechanism, the combination with a carriage, of a stepped stop, a column stop bar, and column stops adjustable along said bar, the latter being pivoted so that when any column stop stands opposite said stepped stop, a movement of the latter will force the column stop and bar to swing out of the way.

In testimony whereof I have signed my name to this specification, in the presence of two subscribing witnesses.

BÉLA GEREBEN.
